UNITED STATES PATENT OFFICE.

ERNST KEPPEL, OF NUREMBERG, GERMANY, ASSIGNOR TO THE FIRM BLECHSPIEL-WARENFABRIK JOHANN DISTLER, OF NUREMBERG, BAVARIA.

MECHANICALLY-MOVED TOY.

Application filed October 23, 1926, Serial No. 143,652, and in Germany January 13, 1926.

This invention relates to a mechanically moved toy of that kind in which in a socket-like casing coupling elements and supporting arms are arranged which are rotated in a circle by means of a clockwork and influenced by an action from the outer side, said supporting arms moving figures which project from the casing, so that the one figure catches up with another figure whereby for instance a pursuit is imitated.

From toys of this kind and of known construction the toy according to the invention differs by its special construction, essentially with regard to the arrangement of the inner coupling elements and of the arrangement which limits the pursuit-proceeding to a predetermined duration of rotation, whereby the toy is made much more interesting, the construction being simplified and the cost of manufacturing reduced.

With this object in view one of the arms, which carry the toy-figures, is connected to the axle of the clock-work, the other supporting arm being loosely mounted on this axle, but pulled along by the positively operated supporting arm with the aid of a coupling lever, oscillatably mounted on said arm, an adjusting- and brake lever being arranged for the supporting arms at the side of the track, so that it partly embraces these arms and so that it can be operated from the outer side.

According to the direction in which this adjusting brake-lever is moved the loose arm is braked, i. e. its toy-figure is kept back so that the moving supporting arm advances until, by means of the adjusted coupling lever, the loose supporting arm with its figure is drawn up to the end of said brake-lever.

A toy according to the invention is shown, by way of example, in the accompanying drawing in which

Fig. 1 is a front elevation partly in section, the base plate dove-tail being omitted.

Fig. 2 is a plan view.

Fig. 3 shows a constructional detail.

Fig. 4 shows in side elevation partly in section a figure imitating a policeman who regulates the traffic.

With a base plate *b* which has dove-tails *a* at the edge, a bottom plate *c* is connected by means of bow-shaped elements *d* gripping over both plates, and which might imitate constructive works of the railway construc-

tion, in such a manner that between the two plates an annular slot *e* is formed. A supporting arm *f* has a vertical support *i* at its outer end which projects through the annular slot *e*. The axle *h* of the clockwork has a winding square *g*. The lever arm *f* has at its outer end a vertical support *i* on which a toy motor car or any other toy figure *k* is fixed. On the axle *h* a second arm *l* is rotatably mounted which carries on a vertical pin *m* projecting through the annular slot *e* a second toy figure, for instance a cyclist *n*. A sickle-shaped two-arm lever *o*, *p* is rotatably mounted on the supporting arm *f* which is controlled by a two-armed lever *r*, *s* pivotally mounted on a pin *q* fixed on the lower surface of the base plate *b*. The arm *r* of this two-armed lever is adapted to be operated by means of a handle *u* which projects through an arc-shaped slot *t* of the base plate. The arm *r* carries a stop nose *v* projecting towards the clockwork and having at one side a downwardly projecting flange *w* serving as abutment. The other arm *s* of the two-armed lever carries a downwardly projecting pressure plate *x* which cooperates with a slide *z* guided on the arm *l* and controlled by a spring *y* or with an upwardly directed abutment plate 2 of this slide. The slide *z* carries a pin 3 upwardly projecting through the arm *l* and adapted to be brought into or out of the range of the arm *p* of the catch lever according to the position of slide *z*. The length of the stop nose *v* and the projection of the pressure plate *x* are selected so that the coupling lever *o*, *p*, which in the position shown in Fig. 3 and at the extreme position of the adjusting lever *r*, *s* shown in this figure, is out of engagement with the pin 3 of the slide *z* pressed on by the pressure plate *x*, so that after the winding up of the clockwork the toy figure *k* alone is moved in a circle. If the arm *r* of the adjusting lever *r*, *s* is then moved inwards the slide *z*, owing to the backward movement of the pressure plate *x* is shifted in outward direction so that the arm *p* of the coupling lever, which bears onto the abutment 4 of the supporting arm *f*, grips the pin 3 and takes along the rotatable supporting arm *l* and the toy figure mounted on the same so that it looks as if the second toy figure pursues the first toy figure. If the lever *r* is brought into the inner ex-

treme position indicated in Fig. 3 in dash lines, the arm *o* strikes against the abutment plate *w* so that, when the supporting arm *f* continues to move, the arms *o*, *p* of the coupling lever are folded over onto this supporting arm *f*. At the same time the supporting arm *l*, owing to the sickle-shape of the arm *p* of the coupling lever which grips the pin *3*, is pulled on at accelerated speed so that the supporting arms *f* and *l* are the one directly behind the other and that the toy figure *n* has come up with the toy figure *k* which has been stopped by the supporting arms *f* striking against the abutment plate.

In this manner the police regulation valid in the United States can be reproduced in the game that the traffic-policeman observes a driver of a motor car, for instance, from under one of the imitation railway constructions, pursues him and forces him finally to stop.

The toy figure which represents the traffic policeman mounted on a bicycle can stop under a bridge or the like as the pressure plate is arranged underneath such a superstructure. As long as at the releasing of the stop nose *v* the projecting slide *z* does not butt against the pressure plate *x* which is in the braking position the loosely rotatable supporting arm *l* is drawn along by means of the coupling lever *p* from the fixed supporting arm *f*. If however the slide *z* strikes against the pressure plate *x* the movable supporting arm *l* is locked and the fixed arm *f* continues to move alone, the coupling arm *p* being turned beyond the catch pin *3* until it strikes against the abutment *4*.

In order to make the game more interesting the arrangement is made that by means of the handle *u* of the two-armed lever *r*, *s* and by abutments *5*, *6* on the stop nose *v* a toy figure which imitates a policeman or the like is moved forward or backward as these abutments *5*, *6* of the adjusting lever are coupled with a projection *7* of the bottom plate *8* of this toy figure *9*. Underneath the base plate an inclined guide *10* is arranged with which a connecting rod *11* of the arm *13* of the toy figure *9*, said arm having a crank *12*, cooperates in such a manner that when the toy figure *9* is advanced the arm *13* is raised by the inclined guide *10* so that the toy figure *k* is stopped.

55 I claim:—

1. A mechanically operated toy comprising in combination a base plate, two toy figures on said base plate, a clockwork, a supporting arm for one of said toy figures rigid with and operated from said clockwork, a supporting arm for the other toy figure loosely connected to said clockwork, a two-armed adjusting lever, a pressure or brake plate on the outer end of one of the arms of

said adjusting lever, means for operating said adjusting lever from the outer side, a spring controlled slide shiftable on said loose supporting arm, a sickle-shaped two-armed coupling lever pivotally mounted on said fixed supporting arm, a pin on the inner end of said slide adapted to come into the range of said coupling lever, a brake arm at the free end of the second arm of said adjusting lever, a brake nose on said brake arm and adapted to act upon said coupling lever so that, if said adjusting lever is operated said brake arm releases said coupling arm and said slide is pushed back by said pressure or brake plate and said pin of said slide comes out of the range of said coupling lever whilst when said slide is released said coupling lever catches said pin and pulls said loose supporting arm gradually towards said fixed supporting arm until both supporting arms are stopped by said brake nose.

2. A mechanically operated toy comprising in combination a base plate, two toy figures on said base plate, a clockwork, a supporting arm for one of said toy figures rigid with and operated from said clockwork, a supporting arm for the other toy figure loosely connected to said clockwork, a two-armed adjusting lever, a pressure or brake plate on the outer end of one of the arms of said adjusting lever, means for operating said adjusting lever from the outer side, a spring controlled slide shiftable on said loose supporting arm, a sickle-shaped two-armed coupling lever pivotally mounted on said fixed supporting arm, a pin on the inner end of said slide adapted to come into the range of said coupling lever, a brake arm at the free end of the second arm of said adjusting lever, a brake nose on said brake arm and adapted to act upon said coupling lever so that, if said adjusting lever is operated said brake arm releases said coupling arm and said slide is pushed back by said pressure- or brake plate and said pin of said slide comes out of the range of said coupling lever, whilst when said slide is released said coupling lever catches said pin and pulls said loose supporting arm gradually towards said fixed supporting arm until both supporting arms are stopped by said brake nose, a third toy figure at the side of the base plate, a movable arm of said toy figure, a connecting rod hingedly mounted on said arm, an inclined guide underneath said third toy figure, a stop nose at the upper end of said inclined guide, and means for connecting said connecting rod with said adjusting lever so that the arm of said third toy figure is lifted when said first mentioned two toy figures are stopped.

In testimony whereof I affix my signature.

ERNST KEPPNER.
